PERCY GERALD OWEN,
BY *Gutherfordhaugh Co.* ATTYS.

UNITED STATES PATENT OFFICE.

PERCY GERALD OWEN, OF VANCOUVER, BRITISH COLUMBIA, CANADA.

GAS-STOVE.

1,173,851.

Specification of Letters Patent. Patented Feb. 29, 1916.

Application filed February 1, 1915. Serial No. 5,495.

To all whom it may concern:

Be it known that I, PERCY GERALD OWEN, a subject of the King of Great Britain, and a resident of the city of Vancouver, in the 5 Province of British Columbia, Canada, have invented certain new and useful Improvements in Gas-Stoves, of which the following is a specification.

My invention relates to improvements in 10 gas stoves, with more particular reference to the means of lighting same, and the object of my invention is to devise a simple and inexpensive means adapted to be operated by the gas cock when opening same so as to 15 light the gas and thus make the stove self-lighting, thereby doing away with the necessity of using matches or other exterior sources of lighting and providing a great convenience where such stoves are used. I 20 attain this object by the means illustrated in the accompanying drawings in which—

Figure 1 is a plan view of a portion of a gas stove, showing the application of my device thereto. Fig. 2 is a view of the lever 25 which carries the platinum element.

Similar figures of reference indicate similar parts throughout the several views.

1 indicates a fragmentary portion of the top of a gas stove having the usual gas ring 30 2 provided with the gas jets 3, to which ring is led, in the ordinary manner, the branch pipe 4 from the main gas pipe 5.

6 indicates the gas cock provided with a suitable handle 7. 35 Secured into the stove at a suitable position is a suitably insulated pin 8, on which is swingably mounted a lever 9, which lever is provided with an extension 10 and which extension carries a boss 11, all as shown in

40 Figs. 1 and 2. Rigidly secured into the boss 11 is a tubular member 12 the outer extremity of which is, when in operation, in close proximity to one or two of the gas jets 3. Carried by the tubular member 12 at its 45 outer extremity is a platinum element 13. A finger 14, of sufficient length to engage the lever 9, is secured to or formed integrally with, the cock, as shown in Fig. 1. The handle 7 may be suitably insulated

50 from the head of the cock, if desired, or the insulating of the various parts may be carried out in any approved fashion where necessary for the protection of the operator. A spring 15 is provided for the purpose of 55 returning the tubular member 12 to its normal position after the stove is lighted, and

a spring 16 is provided for returning the cock to its normal full open position. The spring 16 may be secured to the body of the cock 6, or to any other suitable stationary 60 part and positioned so that it will be acted upon and compressed by the cock, or the handle as shown in Fig. 1, as soon as the cock is moved past its normal full open position when lighting the stove, as herein- 65 after described.

17 and 18 indicate the wires of an electrical circuit, receiving their current from the house lighting circuit or from a battery.

19 indicates a branch wire from wire 17 to the finger 14 and 20 indicates a branch wire from wire 18 to the platinum element 13, while 21 is a "ground" wire from the platinum element to any suitable point and may be connected to the lever 9 as shown in 75 Fig. 1, from which it will be seen that a branch circuit is formed through which current may be passed to the platinum element 13 and which circuit may be completed or broken by the finger 14 when contacted 80 with, or moved away from, the lever 9.

Having thus indicated the principal parts of my invention I will now indicate the manner in which it operates. As is well known, when the stove is not in use, the gas 85 cock 6 is in the shut position, the handle 7 being then at right angles to the dotted position of the handle shown in Fig. 1. The tubular member 12 is then its normal position, as shown dotted in Fig. 1, being held 90 in that position by the spring 15. To now light the stove, the handle 7 is moved to open the cock 6 and is carried around a little past the full open position so as to engage the point of the lever 9 and thus swing the tubular member 12 from the dotted position until its extremity bearing the platinum element 13 is close to the gas jets 3, as shown in full in Fig. 1. As soon as the finger 14 95 contacts with the lever 9 the circuit through the platinum element is completed, causing it to glow sufficiently to light the gas at the nearest jets, which in turn light all the rest. The gas being lighted, the handle 7 is released, whereupon the spring 16 brings it 100 back to the dotted position, when the cock will be in its normal full open position, while the spring 15 returns the tubular member 12 to its normal position clear of the flame, from which it will be seen that 105 the circuit through the platinum element 13 is then broken, as the finger 14 does not con-

tact with the lever 9 when the handle 7 is in the full open position, as shown dotted in Fig. 1. In order to insure a full supply of gas at the moment of lighting, the port in the cock 6 is made larger than usual so that its area will not be restricted by the movement of the cock past the usual full open position when lighting the gas.

It will be seen, therefore, that I have devised a simple and inexpensive means whereby gas stoves are made self-lighting, and which is of great utility and convenience.

What I claim as my invention is:

The combination with a gas stove having the usual gas ring provided with gas jets and gas inlet cock, of a normally broken electrical circuit, an igniting element disposed in said circuit swingably supported

normally at a distance from said gas ring, means for swinging said igniting element into close proximity to said gas jets and for simultaneously closing said circuit to heat said element, said means being adapted to operate only when said inlet cock is moved past its normal full open position, means for returning the igniting element to its normal position when the gas inlet cock is returned to its normal full open position, and spring means for returning said inlet cock to its normal full open position.

Dated at Vancouver, B. C., this 11th day of January, 1915.

PERCY GERALD OWEN.
